V. NOLE

CURTAIN SUPPORTING ATTACHMENT

Filed Jan. 14, 1919

INVENTOR:
Vito Nole,
BY
Fraenzel and Richards,
ATTORNEYS.

UNITED STATES PATENT OFFICE.

VITO NOLE, OF NEWARK, NEW JERSEY.

CURTAIN-SUPPORTING ATTACHMENT.

Application filed January 14, 1919. Serial No. 271,061.

To all whom it may concern:

Be it known that I, VITO NOLE, a citizen of the United States, residing at Newark, in the county of Essex and State of New Jersey, have invented certain new and useful Improvements in Curtain-Supporting Attachments; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in adjustable curtain-supporting means for windows; and, the present invention has reference, more particularly, to a novel attaching means, in the form of plates which are adapted to be secured to the window-casing, or the like, and with which the supporting bar or rod is removably and adjustably connected, the device being also adapted for use as a towel-rack, or other suitable supporting means.

The present invention has for its principal object to provide a novel supporting means or carrier of the general arrangement and combination of devices and parts to be hereinafter more particularly set forth, the same comprising a pair of supporting fixtures or plates adapted to be easily secured in fixed positions to a window-casing, or wall, and a supporting rod or bar provided at its bent or curved end-portions with slides adapted to be slidably and removably mounted with relation to said fixtures or plates, so that the supporting bar or rod upon which the curtain or towel is supported or carried, can be easily and quickly removed, when it is desired to clean the window, or for other purposes, without the necessity of having to remove the supporting fixtures, thus avoiding the necessity of removing said fixtures or plates and requiring tedious and difficult adjustments, when replaced, and at the same time preventing the marring of the wood, with the constant replacing and removing of the said rod or bar-supporting fixtures or members.

Other objects of the present invention not at this time more particularly mentioned will be clearly understood from the following detailed description of the same.

With the various objects of the present

invention in view, the said invention consists, primarily, in the novel curtain-support or carrier for windows hereinafter set forth; and, the invention consists, furthermore, in the novel arrangements and combinations of the several devices and parts, as well as in the details of the construction of the said parts, all of which will be more fully described in the following specification, and then finally embodied in the clauses of the claims which are appended to and which form an essential part of the said specification.

The invention is clearly illustrated in the accompanying drawings, in which:—

Fig. 1 is a front view of the upper portion of a window-casing and a curtain-supporting means secured in position to said window-casing, the same illustrating one embodiment of the principles of the present invention; and Fig. 2 is a view of the attachment, looking in the direction of the arrow X in said Fig. 1.

Fig. 3 is a vertical section taken on line 3—3 in said Fig. 1, said view being made on an enlarged scale; and Fig. 4 is a horizontal sectional representation, taken on line 4—4 in said Fig. 1, said view being also made on an enlarged scale.

Similar characters of reference are employed in all of the said above described views, to indicate corresponding parts.

Referring now to the several figures of the drawings, the reference-character 1 indicates the upper portion of a window-casing, door-frame, or the like, to which are secured, as shown in Figures 1 and 2, the previously mentioned supporting fixtures 2 and 3, by means of screws 4, or other suitable fastening means. In the construction represented in Figures 1 to 4 inclusive, each fixture or element 2 and 3 has its marginal edge-portions, which extend vertically when secured to the window-casing or door-frame, 100 bent over upon the face of each plate, the lower portions 5 being forced down tightly upon the face of each plate, but the upper portions 6 being bent so as to provide suitable guiding spaces 7, as will be clearly seen from an inspection of Figures 3 and 4 of the drawings. The outwardly extending parts 8 between said lower portions 5 and said upper portions 6 provide suitable supporting stops 8, the purposes of which will 110 be clearly understood from an inspection of Figures 1 and 3.

Slidably and removably disposed in the said guiding spaces 7 of the respective fixtures or elements 2 and 3, with their lower marginal edge-portions 10 resting upon said stops 8 are suitably formed slide-plates 9, each plate having suitably secured thereto, by means of a thimble 11, or in any other manner, the end-portions, as 14, of a pair of supporting rods 12 and 13. Usually these rods are made so that the end-portion 15 of the one rod 13 will slip into the tubular end-portion 16 of the other rod 12, or vice versa, for proper adjustment of said rods 12 and 13 with relation to said fixtures or elements 2 and 3, as will be clearly understood. That the end-portions 14 and 15 of said rods can be readily brought into their telescopic relation, the smaller of said rods, as 13, may have suitably secured in its tubular end-portion 15, a member 17 having a pointed or similarly shaped end 18, as indicated in dotted outline in Figure 1 of the drawings, the purpose of which will be clearly understood from an inspection of said Figure 1.

Of course I am aware, that changes may be made in the various arrangements and combinations of the several devices and parts, as well as in the details of the construction of said parts, without departing from the scope of the present invention as set forth in the foregoing specification, and as defined in the clauses of the claims which are appended to the said specification. Hence, I do not limit my present invention to the exact arrangements and combinations of the various devices and parts as described in the said specification, nor do I confine myself to the exact details of the construction of the said parts as illustrated in the accompanying drawings.

I claim:

1. A curtain-attachment for windows, and the like, comprising a pair of rectangularly-shaped supporting elements adapted to be secured in fixed positions, each supporting element having its vertically dis-

posed margins bent over into positions parallel with the face of said supporting element, the upper portions of said bent margins being spaced from said face to provide guide-ways, thereby to provide a stop between each tightly forced down portion and the guide-way, the lower portion of each supporting element beneath said stops being provided with an exposed perforation for the reception of a securing means, a pair of slide-plates movably disposed between the guide-ways of the respective supporting elements, said slide-plates normally resting upon said stops, and a supporting rod connected at its ends with said slide-plates.

2. A curtain-attachment for windows, and the like, comprising a pair of rectangularly-shaped supporting elements adapted to be secured in fixed positions, each supporting element having its vertically disposed margins bent over into positions parallel with the face of said supporting element, the upper portions of said bent margins being spaced from said face to provide guide-ways, thereby to provide a stop between each tightly forced down portion and the guide-way, the lower portion of each supporting element beneath said stops being provided with an exposed perforation for the reception of a receiving means, a pair of slide-plates movably disposed between the guide-ways of the respective supporting elements, said slide-plates normally resting upon said stops, and a supporting rod connected at its ends with said slide-plates, said rod comprising a pair of telescopically arranged tubular members, and a pointed inserting member extending from one of said tubular members.

In testimony, that I claim the invention set forth above I have hereunto set my hand this 9th day of January, 1919.

VITO NOLE.
